SHOE CONSTRUCTION

Martin H. Reymond, Binghamton, N. Y.

Application May 2, 1931, Serial No. 534,667

10 Claims. (Cl. 12—142)

The principal object of this invention is to provide a shoe in which the flexing portion between the tip and the arch is constructed in such a manner that the flexure takes place in regular predefined ridges in the upper of the shoe. This invention further involves particular characteristics in such ridges. It further involves the process of forming these ridges by incorporation in the last. It further involves such a process including certain other characteristics.

In the past, with the usual methods of constructing shoes, the upper has been permitted to flex in an irregular manner at the principal flexing portion (commonly called the vamp) between the tip and the arch. This irregular flexure is not only unsightly and incompatible with the artistic beauty of many shoes, but it also contributes toward discomfort and deterioration. The irregular flexure may cause discomfort by pressing on some sensitive portion of the foot. The lack of allowance for flexure of the toes downward as well as upward may also cause discomfort. This is particularly noticeable when climatic conditions are such as to cause the upper to shrink, bowing up the sole and hindering the toes from proper freedom of contact with the ground. The construction of the flexing portion in ridges, somewhat after the fashion of a bellows, permits such freedom. This ridge or bellows construction also tends to help ventilate the shoe as it flexes. This ridge construction also reduces the tendency of shoes of the usual construction to wear at the vamp, by eliminating the strain when toes bend downward, and by eliminating the tendency of shoes without ridges to flex at the weakest point in the upper material thus concentrating the greatest strain where it can least be withstood.

Referring to the drawing: Figure 1 is a top view of a right foot shoe, illustrating the ridge construction that has been described in general terms. Figure 2 is a side view of such a shoe. Figure 3 is a side view of a last, on which are incorporated the ridges it is desired to incorporate into the shoe. These ridges are shown incorporated onto this last by means of a toe cap so constructed as to facilitate removal from the shoe. Figure 4 illustrates one method of setting the upper into the valleys between ridges. This is a cross sectional view of a plane located as indicated by 4—4 in Figure 1. However in Figure 4 the last and setting means, which do not appear in Figure 1, are shown.

As a makeshift proposition it might be possible to incorporate ridges such as described into

already finished shoes, by clamping the vamp between jaws containing such ridges, or by inserting a secondary last containing such ridges, and to some extent stretching and setting the upper into such ridges by pressure, heat, stiffening compound, or other elements.

For best results, however, these ridges should be built into the shoe in the first place. It is conceivable to accomplish this by building into the upper material stiffening ribs or flexible channels or both along the lines of the desired ridges. A preferred way of building these ridges, not involving the necessity of such ribs or channels, is illustrated in the drawing and described in further detail below.

By this preferred method, the desired ridges are incorporated onto the last. These ridges on the last are numbered 1, 2, and 3 in Figure 3. These ridges in the shoe are similarly numbered 1, 2, and 3 in Figures 1, 2, and 4. Of course the number of ridges is not limited to three either as a maximum or as a minimum. The number 3 is merely illustrative. Preferably these ridges on the last are incorporated onto a removable cap over the toe of the last. See Figure 3, cap 4 over last 5. This makes it possible, after the shoe is completely assembled, to remove last 5, and then by dropping cap 4 down toward the sole to easily remove this cap. If the ridges were solid on the last, it would be difficult to remove this last from the shoe.

With the ridges thus incorporated onto the last, the upper can be moulded over these ridges in the lasting operation. To insure the permanency of the location of these ridges, they can be set by ironing in or by some other method involving pressure alone or pressure and heat. They can be further made permanent by application of some stiffening material to the upper before this setting operation. They can further be made permanent by the application of a suitable adhesive backing behind the upper, which can be incorporated with the upper and perhaps also with the lining in the setting operation. Referring to Figure 4, 8 represents the outside upper material, 9 represents such an adhesive backing, and 10 represents the lining. One means of setting the upper into the valleys between ridges on the last is illustrated by 6 and 7 in Figure 4. These may be cords adapted to be pulled tightly around the last into these valleys. Or they may be heavy elastic bands adapted to fit tightly around the last. After being subjected to whatever heat process or other setting process desired,

these setting means may be removed, leaving the ridges permanently incorporated in the shoe.

There are certain advantageous general characteristics of such ridges that will now be described.

First it is advantageous that the greatest height of these ridges should be at the top of the shoe. Line 4-4 in Figure 1 is approximately at the top of the shoe where these are highest. These ridges 10 gradually taper off to negligible height at the sides of the shoe near the sole. The greatest height is at the top because that is where the greatest flexure takes place. The height is negligible at the sides near the sole as here the flexure 15 is comparatively negligible. Also this makes possible lasting the upper to the sole without the complication of ridges at this point.

Second it is advantageous that such ridges flare outwardly toward the rear at least on the outside 20 of the shoe, because the construction of the human foot is such that the lines of flexure have substantially this characteristic. Such outward flaring is also advantageous from the standpoint 25 of cooperation with the natural flexure of the sole. This sole flexure is spread over a considerable length rather than concentrated at any one place.

Variations in the particular constructional features illustrated and described are of course possible. These particular constructional features 30 are merely illustrative of preferred ways of carrying out this invention. Similar variations are also possible in the particular process described for achieving such constructional features. The 35 definition of the exact scope of the present invention, including all possible variations, and also including particular preferred variations, has been attempted in the appended claims.

Having thus described the invention, what is 40 claimed is:

1. A shoe in which the principal flexing portion of the upper between the tip and the arch includes predefined regular ridges of flexure, said ridges decreasing in altitude to substantially negligible altitude as they approach the sole.

2. A shoe in which the principal flexing portion of the upper between the tip and the arch includes predefined regular ridges of flexure, said ridges decreasing in altitude to substantially negligible altitude as they approach the sole, and said ridges being moulded in said upper wholly above the normal inner surface of said shoe.

3. A shoe in which the principal flexing portion of the upper between the tip and the arch includes predefined regular ridges of flexure, said ridges decreasing in altitude to substantially negligible altitude as they approach the sole, said

ridges being moulded in said upper wholly above the normal inner surface of said shoe, and said ridges running generally crosswise of the shoe and curving toward the rear on the outside of the shoe.

4. A shoe in which the principal flexing portion of the upper between the tip and the arch includes predefined regular ridges of flexure, said ridges decreasing in altitude to substantially negligible altitude as they approach the sole, and said ridges running generally crosswise of the shoe and flaring apart on the outside of the shoe as they approach the sole.

5. In a shoe, an upper having the principal flexing portion between the tip and the arch reinforced with a stiffening material and having predefined regular ridges of flexure formed in said portion and permanently retained by said stiffening material.

6. In a shoe, an upper having the principal flexing portion between the tip and the arch reinforced with an adhesive backing material and having predefined regular ridges of flexure formed in said portion and permanently retained by said adhesive backing material.

7. The process of constructing a shoe, comprising: incorporating elevated ridges onto a cap fitting over the last, lasting the upper over the composite last thus formed, bottoming the shoe, removing the last without the cap, and finally 10 removing the cap first pressing it downward away from the moulded ridges in the shoe.

8. The process of constructing a shoe, comprising: incorporating elevated ridges onto a cap fitting over the last, lasting the upper over the 11 composite last thus formed, intensifying the ridges in the upper by simultaneously setting the upper into the valleys between ridges on the cap, bottoming the shoe, removing the last without the cap, and finally removing the cap.

9. The combination of: a last, ridges mounted on said last wholly above the normal surface of said last, said ridges running generally crosswise of the last between the tip and the arch, and said ridges decreasing in altitude to substantially negligible altitude as they approach the sole.

10. The combination of: a last, ridges mounted on said last wholly above the normal surface of said last, and means for pressing the upper of a shoe moulded on said last between all said ridges 1 simultaneously, said ridges running generally crosswise of the last between the tip and the arch, and said ridges decreasing in altitude to substantially negligible altitude as they approach the sole.
